D. 335,358 5/1993 Cole D25/124

Primary Examiner—Doris Clark

[57] CLAIM

The ornamental design for a casement sash, as shown and described.

DESCRIPTION

FIG. 1 is a perspective view from above the casement sash; and,

FIG. 2 is an end view of the casement sash.

The casement sash is broken away in the center to indicate indeterminate length.
